CLAIM

The ornamental design for an animated avatar for a display screen, as shown and described.

DESCRIPTION

FIG. 1 is a front view of the first image in the sequence for an animated avatar for a display screen showing our new design; FIG. 2 is a front view of the second image thereof; FIG. 3 is a front view of the third image thereof; FIG. 4 is a front view of the fourth image thereof; FIG. 5 is a front view of the fifth image thereof; FIG. 6 is a front view of the sixth image thereof; FIG. 7 is a front view of the seventh image thereof; FIG. 8 is a front view of the eighth image thereof; FIG. 9 is a front view of the ninth image thereof; FIG. 10 is a front view of the tenth image thereof; FIG. 11 is a front view of the eleventh image thereof; FIG. 12 is a front view of the twelfth image thereof; FIG. 13 is a front view of the thirteenth image thereof; and, FIG. 14 is a front view of the fourteenth image thereof.

The appearance of the animated avatar sequentially transitions between the images shown in FIGS. 1-14. The process or period in which one image transitions to another forms no part of the claimed design. The broken line drawing of a portion of a display screen in all views is for illustrative purposes only and forms no part of the claimed design. The broken line showing on the remainder of the avatar image is for environmental purposes only and forms no part of the claimed design.
